UNITED STATES PATENT OFFICE

EDWARD TROY HAILS, OF MONTGOMERY, ALABAMA

INDIVIDUAL TOWEL CABINET

Application filed January 25, 1928. Serial No. 249,252.

This invention relates to an improvement in individual towel cabinets in which it is contemplated that a plurality of individual towels are suitably assembled and folded so that they will present free ends to enable them to be pulled out successively into position for use.

My invention contemplates the provision of a cabinet adapted to enclose a plurality of assembled towels which may generally be referred to as a towel pack, and it has access means by which the uppermost or foremost towel of the pack can be reached by the user and drawn out of the cabinet.

It is a distinctive feature of my invention that the pack of towels shall be so arranged with relation to the said access means that when a used towel is released it will be adapted, when drawn back into the cabinet, to hang below the clean towels of the pack and out of position that will interfere with access to the remaining clean towels of the pack. It is also contemplated that the soiled towels as they hang in the cabinet will be concealed.

My invention also contemplates the employment of an automatic means preferably a gravitating element such as a door which is operable to give access to the towels in the cabinet as a means for effecting the retraction of the soiled towel into concealed position in the soiled towel portion of the cabinet. Preferably the access opening in the cabinet is closed by a vertical sliding door which, when released, gives access to the clean towels of the pack and which, as it drops, will engage the soiled towel, and the latter having been released by the user will retract it into the cabinet.

Another distinctive feature of my invention has relation to the cabinet itself which is adapted to receive the towel pack. This cabinet acts on a different principle from any with which I am familiar in that the slide or door, which must be opened or displaced to give access to the towel pack, must itself be supported by the pull on the fresh towel while same is in use, the door being adapted, as soon as the used towel is released, to fall by gravity and displace such towel, leaving the next clean towel accessible in the

pack when the door is again opened. I claim broadly the combination with associated individual towels, of automatic means to displace the used towels successively into the appropriate storage space therefor in the cabinet, the means being set ready to operate, responsive to any step incidental to the withdrawal of a fresh towel and held so set until the towel has been used and released, when the means is free to act and will automatically displace such last used towel.

Another distinctive feature of my invention lies in the fact that this slide is suitable for very effective advertising display in that its normally concealed portions, which become exposed when it is raised to give access to the towels and when it is supported by the towel in use, can both present any desired display and they will do so under conditions that will make it particularly impressive to the user. It is contemplated that the cabinet can be variously modified, according to the conditions of service and character of use contemplated, and can be readily adapted to house any supplemental equipment that may be needed in connection with the towel cabinet, but as my invention is more particularly concerned with the matter of handling the towels I shall not show the cabinet with any accessories. My invention also comprises novel features of construction in the manner of assembling the towels in a pack and in clamping them between clamp plates removably mounted in the cabinet, and for the utilization of the clamp plates to support the clean towels always so as to present the foremost towel in a predetermined position with relation to the access means.

My invention further comprises the novel details of construction and arrangements of parts, which in their preferred embodiments only are illustrated in the accompanying drawings which form a part of this specification, and in which:—

Fig. 1 is a front view of the cabinet in closed position.

Fig. 2 is a similar view showing the cabinet with the sliding door fully raised to expose the towel pack and present the upper advertising display.

Fig. 3 is a central vertical cross-sectional view taken through the cabinet showing the sliding door supported by a towel drawn out for use with its lower advertising display presented.

Fig. 4 is a fragmental view taken on the line 4—4 of Fig. 2, showing the fresh towel drawn out before the sliding door is lowered into position to rest on, and be supported by it.

Fig. 5 is a detail plan view of the towel pack in its mounting clamp.

Fig. 6 is a diagrammatic view illustrating the pull mechanism for lifting the sliding door.

Fig. 7 is a detail perspective view of the back clamp member.

Similar reference numerals refer to similar parts throughout the drawings.

In the embodiment of my invention illustrated, I show merely in formal manner a cabinet comprising a bottom 7 and a front wall 8 having a transverse intermediate opening 9 and above it a mirror 10. The cabinet comprises end walls 11 and 12, a top wall 13 and a hinged back wall 14. The side walls 10 and 11 adjacent to the front wall 8 are provided with vertical slots 15 extending from the top wall well below the opening 9 and forming aligning guides for a sliding door 16, which is provided in its lower portion with a demountable advertising panel 17 and at its center with a pin 18 connected by a suitable pull cord or cable 19, running over pulleys 20 and 21, to a knob 22 slidable in a slot 23 in the end wall 11. This is typical of any convenient and inexpensive means for raising the door in its guides 15 to clear the front opening 9.

The upper end of the door when raised is adapted to engage a top panel 24 carrying a dependent advertising slide 25, this panel 24 being normally seated flush in a transverse opening (see Fig. 4) in the top 13. Fig. 4 shows this panel raised so as to expose to view an advertising display on the slide indicated within the border lines 27 in Fig. 2. This slide is long enough to overlap the top of the door in the latch's lowered position as shown in dotted lines, Fig. 3, and this slide is also received in the upper part of the door guides 15. As will be seen by Fig. 4, when the knob is fully depressed, the door is raised to expose the opening 9 and thus access is had to the interior of the cabinet for the purpose of withdrawing therefrom a fresh towel.

While the advantages of my invention are applicable to various ways of assembling and presenting the clean towels so that they can be successively used, I consider the arrangement which will now be described as that best suited for use with my improved type of cabinet.

I show the individual towels as formed by the desired number of layers of towelling,

each layer 28 in length being sufficient to provide material at its center to form a towel rod loop and for each end to form an individual towel. These layers 28 are superimposed and then folded about each other at 70 their center and stitched together across their width at 29, thereby producing a closed bight to form the loop for the towel rod 30. Each individual towel as thus formed by a free end of a layer 28 is then folded one time upon itself and the folded towels are interposed in a clamp comprising a back plate 31 and a front plate 32. A pair of elastic bands 33 are passed length wise under the back plate 31 and then up through guide 34 formed in the ends of said plate. The free ends of the straps are connected to cross bars 35 notched at 36, and the bands are adapted to be received in notches 37 cut in the ends of the front plate 32, the cross members 35 being adapted to be 85 engaged over button-head stop pins 38 on the top clamp plate 32. The front edge of the plate 32 is cut away at 39 to give a better opportunity to grip the free end of the uppermost towel in the clamp, and the back plate 31 is covered with felt or like material 40 so that the pack of towels will be frictionally held thereon while they are free to be drawn from under the smooth under surface of the front plate 32.

Each clamp plate 31 and 32 at the center of its ends is provided with a mounting pin 41, these pins being adapted to be received in guide slots 42 formed in the end walls 11 and 12, these slots being downturned at their forward ends so as to hold the clamp in mounted position when its front plate 32 engages the stop pin 43 and is then engaged by the spring-pressed dog 44, which presses this plate against the stop 43 and holds its pins 41 in the downturned ends of the slots 42. A towel rod 30 is slipped through the bight in the towel pack and the ends of this rod are free to slide through guide slots 45 therefor in the end walls 11 and 12. The slots 42 and 45 rise from the rear towards the front of the cabinet and when the last towel has been drawn from the pack and used, the pack is supported only by the towel rod 30 which is free to run down the slots 45 and to be discharged as soon as the cabinet is opened.

It will be noted that the towel rod, when in operating position (see Fig. 3), stands near the bottom level of the opening 9 and that the towel pack is inclined forwardly and downwardly so that the uppermost towel will always have its free end exposed approximately in line with the center of the opening 9, thus making it equally convenient to pull out the first as the last towel. The rod resists the outward pull on the towels as they are being used.

In the operation of the cabinet, assuming the parts in the position shown in Fig. 1, the user grasps the knob 22, depresses it to 130

the bottom of the slot 23 and thereby raises the door 16 to the position shown in Fig. 4, fully exposing the towel pack to view through the opening 9, and at the same time presenting the advertising display 27, (see Fig. 2). While holding the knob down with one hand the user grasps the free end of the uppermost towel opposite the cut away portion 39 and draws the towel out by pulling it out from under the smooth clamp plate 32. The towel, when pulled out, assumes the position shown in Fig. 4, and the user thereupon releases the door 16, which drops down upon and is supported by the towel in the manner shown in Fig. 3, and continues to be so supported while the towel is being used. When standing in this semi-lowered position, the door exposes the advertising panel 17 opposite the opening 9 where it will best attract the attention of one using the towel. As soon as the towel has been used and its free end is released, the weight of the door will carry it down to its dotted position shown in Fig. 3, thus automatically displacing the soiled towels into any suitable space provided therefor in the lower portion of the cabinet. This operation is repeated until all of the towels are used. When the door drops it conceals both advertising displays and closes the opening 9, leaving exposed directions for use of the cabinet which are printed on the door and which will then be visible through the opening 9. It is contemplated that the cabinet will be mounted by attaching its back wall 14 to the wall or other support and that the cabinet is free to swing outwardly on the hinges 46 to a position at right angles to the wall or support, when it is desired to recharge it with towels. When the cabinet is thus opened, as has been explained, the soiled towels will be suspended from the towel rod and the latter will be ready to be slipped out of the inclined slots 45. Thereupon, the towel rod is removed from the soiled towel pack and inserted in the bight of a clean towel pack and this towel pack is then mounted in the manner described and held in position by the latch 44, whereupon the cabinet is swung back against the back wall and latched and is then ready for use. The importance of the frictional cover for the back clamp plate 31 will be apparent when it is considered that only the uppermost towel should be drawn out and without a proper frictional means on the back plate 31 to grip the towel pack one or more towels at a time or all of the pack might be pulled out from the clamp. In laundering, all of the towels of a pack are laundered at one time and can be readily folded into the packs and mounted between the clamps. Due to the pressure exerted on the folded towels from the clamp it is not necessary to iron the towels as they will appear flat and smooth as they are drawn out of the clamp. The towel packs as mounted in their clamps at the laun-

dry, can be very conveniently rendered sanitary by wrappings and delivered in this manner to the customer.

While in the apparatus shown, no means to control the manipulation of the door operating knob 22 is shown, it is contemplated that its operation, where such is desired, may be controlled by any standard coin operated mechanism, thus requiring the user to pay a small charge before he can open the cabinet.

Though I have described with great particularity the details of the embodiment of the invention herein shown, it is not to be construed that I am limited thereto, as changes in the arrangement of parts and substitution of equivalents may be made by those skilled in the art without departing from the invention as defined in the appended claims.

Having thus described my invention, what I claim as new and desire to secure by Letters Patent, is:—

1. An individual towel cabinet, comprising means to mount a pack of individual towels in a cabinet, there being an opening in the cabinet whereby a clean towel may be grasped by a user and drawn out of the cabinet, said cabinet having a space above said opening to receive the clean towels and a space below said opening to receive the used towels, and means automatically responsive to the release of a used towel from the grasp of the user to retract such towel into the soiled towel portion of the cabinet.

2. A towel cabinet, having an opening for access to the towels, a plurality of individual towels secured at one end in the cabinet, said cabinet having a space above said opening to receive the clean towels and a space below said opening to receive the used towels, and graviting means, automatically responsive to the release of a towel after its free end has been drawn out through said opening, to displace such used towel portion from position between the clean towels and said opening and into concealment in the soiled towel space of the cabinet.

3. In combination with a towel cabinet having a front opening, a pack of individual towels superimposed in folded position and bound together, clamp plates which receive between them the folded towels and expose the lower end of the foremost towel to be grasped by the user, a support to which the individual towels are secured and means to mount the clamped towel pack in operative position in the cabinet above said support.

4. As an article of manufacture a towel pack of the character described, comprising a plurality of towels connected along their centers and individually folded, and a binder carried by the towel pack and comprising yieldably connected clamp plates adapted to receive and substantially cover the folded towels between them.

5. A towel pack of the character described, comprising a plurality of superimposed towels secured together at their centers and individually folded, a binder for the towels removable therewith from the cabinet formed by plates adapted to clamp the folded towels between them, a hanger means demountable from the cabinet and adapted to engage the several individual towels, and means to engage said clamp plates to support the clean towels above said hanger means.
6. A binding clamp for a plurality of superimposed individual folded towels comprising clamp plates adapted to receive the pack of clean towels between them and expose an end of the foremost towel, the bottom plate having a frictional surface and the top plate a relatively smooth surface engaging the towels, and means yieldably connecting said plates.
7. A towel cabinet having an intermediate opening, a vertical sliding door normally closing said opening, a pack of folded towels comprising mounting means to support them in inclined relation above, and with their free ends opposite, said opening and in position to be drawn out successively through said opening for use, means to raise and open the door, the door being adapted to be supported by a towel while in use and to automatically displace the used towel into the lower portion of the cabinet when the towel is released.
8. A towel cabinet according to claim 7, in which the towel pack comprises clamp plates removable with each individual pack and having end projections, the walls of the cabinet being recessed to receive the said projections, releasable means to mount the clamp plates in the cabinet, and the towel pack comprising a towel rod loop, a towel rod demountable from the loop, and a slot in the cabinet in which the towel rod is removably mounted.
9. In a towel cabinet, means to mount a pack of towels therein in position for the used towels thereof to hang below the pack in substantially concealed position, there being an opening in the cabinet giving access to the cleaned towels of the pack to permit the foremost to be drawn downwardly and out for use, and automatic means to cause a used towel upon its release to assume position hanging along with other used towels of the pack.
10. In a towel cabinet, means to mount a pack of towels therein so that the used towels will hang below the clean towels of the pack in concealed position in the cabinet, there being an opening in the cabinet to permit the foremost clean towel of a pack to be withdrawn for use, and means responsive to gravity to cause a used towel to re-enter and hang concealed within the cabinet.
11. In an individual towel cabinet, a casing having an intermediate opening to give access for drawing out a towel for use, means to mount a pack of towels in the casing above

the opening in position to be pulled down as they are drawn out, and automatic means to retract and release a used towel to assume a concealed position in the cabinet out of the path of the clean towels of its respective pack. 70

12. A cabinet comprising means to mount a plurality of individual towels therein, means operative to give access to the foremost clean towels to retract same after use into the soiled towel portion of the cabinet, the mounting means holding the clean towels above and the soiled towels below said access means. 75

13. A towel cabinet having an opening affording access to towels therein, means to mount a plurality of individual towels in the cabinet opposite said opening, said means comprising a front stationary element mounted in fixed relation to said opening, a movable element, and means causing the latter element 80 to press clean towels against the said front element, a stationary hanger below said elements to which the towels are attached and from which they are adapted to hang after use concealed below said opening, and automatic means to cause the used towels to re-enter and hang concealed in the cabinet. 85

In testimony whereof I affix my signature.
EDWARD TROY HAILS.
